JOSEPH WOOLMAN REEVES, OF PHILADELPHIA, PENNSYLVANIA, AS-SIGNOR TO W. H. FRENCH, OF SAME PLACE.

Design No. 4,513, dated December 13, 1870.

DESIGN FOR A CENTER-PIECE FOR CEILINGS.

The Schedule referred to in these Letters Patent and making part of the same.

I, JOSEPH WOOLMAN REEVES, of Philadelphia, county of Philadelphia, State of Pennsylvania, have invented a Design for a Center-Piece for Ceilings, of which the following is a specification.

The figure in the accompanying drawing represents one-half of a center-piece made in accordance with my design, the other half being precisely similar to that shown.

The most prominent features of the design are the central medallion *a*, the circular molding *b* surrounding the same, the oval beading *d*, and the ornamented spaces *e* within the said beading and outside the circular molding *b*.

The ornamentation of these features is too clearly illustrated in the drawing to need explanation.

The whole may be surrounded with a border *f* or border *g*, or with any other tasty border.

I claim—

1. The central ornamental medallion *a*.
2. The ornamental molding *b*.
3. The ornamented spaces *e*, within the oval beading *d*.
4. The design, as a whole, exclusive of the borders.

In testimony whereof, I have signed my name to this specification in the presence of two subscribing witnesses.

Witnesses:

JNO. B. HARDING,
F. B. RICHARDS.

J. W. REEVES.
